WAKELESS TORPEDO

Robert H. Canfield, Washington, D. C.

Application September 14, 1936, Serial No. 100,684

8 Claims. (Cl. 114—20)

(Granted under the act of March 3, 1883, as
amended April 30, 1928; 370 O. G. 757)

1

This invention relates to a torpedo modified to burn a fuel mixture such that the exhaust gases are absorbable in water and hence do not form a wake of bubbles.

Among the numerous objects of this invention are:

To provide for naval torpedoes a fuel mixture of such nature that the exhausted products of combustion shall be absorbable by water and so will prevent the formation of a wake of bubbles that will betray the course and position of the torpedo to an enemy;

To modify the fuel containers and lubricating mechanism of the torpedo to prevent contact of substantially pure oxygen with oil;

To store the fuel, water and a gaseous supporter of combustion under the same pressure while maintaining the fuel and the supporter of combustion out of contact with each other;

To lubricate the moving parts of the torpedo mechanism with a material other than oil for a brief interval at the beginning of the torpedo run while free oxygen may be present in the after body of the torpedo.

In the drawings:

Fig. 1 is a side elevation view of a torpedo indicating the several divisions thereof;

Fig. 2 is a cross section on the line 2—2, Fig. 1;

Fig. 3 is a fragmentary longitudinal section through the midsection and parts of the flask and after body;

Fig. 4 shows a reciprocating engine arrangement that may be used instead of a turbine;

Fig. 5 is a fragmentary longitudinal section of the after body and the midsection showing the connections between portions of the mechanism directly concerned with the present invention;

Fig. 6 is a view similar to Fig. 5 wherein certain mechanical arrangements are modified.

In torpedoes as heretofore known, the propelling agent is composed of the product of the combustion of a fuel with air, to which is added steam in a predetermined proportion. These gases at high temperature and pressure were used to drive a turbine or other engine which was connected to a well known arrangement of shafts and screw propellers. The expansive gases used in the prime mover are, after use, discharged from the torpedo into the water and because they previously contained a large portion of the non-absorbable gas, nitrogen, they came to the surface as bubbles and gave rise to the surface disturbances known as the wake. This wake afforded a means of detecting the presence and course of the torpedo and an enemy ship, which,

2

warned thereby, could maneuver in such a way as to avoid the torpedo.

I have found that when a fuel composed of compounds of hydrogen and carbon, or of compounds of hydrogen, carbon and oxygen, is burned in the presence of nearly pure oxygen the products of combustion are completely absorbable in water and therefore do not give rise to bubbles when discharged into the water.

When substantially pure oxygen is used to support combustion in the place of compressed air, certain changes in design are necessary because of the fact that oxygen in contact with organic materials, and particularly in contact with oil, produces a mixture which is very easily ignited and may, under certain conditions, be explosive. For this reason it is necessary, in the oxygen torpedo, to prevent contact between compressed oxygen and organic substances, particularly oil.

The naval torpedo comprises a substantially cylindrical shell divided by transverse bulkheads into four sections called respectively, the war-head, the flask, the midsection and the after body. The head in naval torpedoes is filled with explosives and the means for exploding the same. The flask ordinarily contains chambers for the storage of lubricating oil, fuel, water and compressed air, which are connected together to subject the water, fuel and oil to the pressure of the air to supply the force necessary for feeding these substances to the propulsive mechanism.

In Fig. 1, the war-head is designated by the numeral 7, the flask by 8, the midsection by 9 and the after body by 10. As shown in Fig. 2, the space 11 in flask 8 is occupied by substantially pure oxygen under the requisite pressure, the water being shown at 12. Since, for the reasons above given, it is dangerous to permit contact of oxygen with organic substances, the fuel is contained in a collapsible bag or container 13 which is preferably of rubber or suitable rubberized fabric. This permits having the oxygen, the water and the fuel under the same pressure but positively separates the oxygen from the fuel. The fuel container 13 is prevented from moving around in the flask by straps 14 attached to the container and passed around bars 15 that are secured to the flask. Increase and decrease in the cross-sectional area of the container 13 is permitted but longitudinal shifting of the container is prevented by loops 16 secured to the container through which loops are passed the arcuate bars 17 fixed to the flask. Owing to the inequalities

in the material of which the bag 13 is made it may collapse, when the major portion of the fuel has been withdrawn, in such manner as to trap the fuel in the end of the container remote from the discharge orifice and therefore I provide the perforated tube 18 that is radially rigid and extends throughout substantially the length of the container adjacent its lower side, whereby the fuel will be discharged regardless of collapsing of the container.

Oxygen is carried by pipe 19 to a suitable arrangement of start-and-stop valves and reducing valves, indicated by 20, and thence to the pot or combustion chamber 21 where it is mixed with fuel passed through pipe 22 and water carried by pipe 23, the proportions of fuel and water being controlled by valves 24 and 25 respectively. Combustion of the fuel is supported by the oxygen, and the water introduced into the combustion chamber is converted to steam which reduces the temperature and modifies the characteristics of the products of combustion so they are more suited for use as the working substance in the prime mover, which is shown in Figs. 3, 5 and 6 as being a turbine arrangement 26 to which the gases are led from the combustion chamber 21 through pipe 27 and nozzle 28. Turbine wheel 29 is connected to shaft 30 and drives one of the propellers of the torpedo while turbine wheel 31 drives the other propeller through shaft 32.

An alternative mechanism that may be employed instead of the turbine is the two-cylinder reciprocating engine 33 shown in Fig. 4. The piston rod 34 of one cylinder is connected through bevelled gears 35 and 36 and shaft 37 to one of the propellers while the other piston rod 38 drives the other propeller through gears 39 and 40 and shaft 41.

The depth control engine 42 and gyroscopic steering mechanism 43 may be operated by oxygen under high pressure taken from the valves 20 through pipes 44, 45 and 46 until the products of combustion from chamber 21 are sufficient in quantity to operate these devices after which gases and steam are taken from pipe 27 through the pipe 47 whence the expansive gases pass into the pipes 45 and 46 and displace the oxygen.

To avoid the danger of lubricating the turbine and other moving parts with oil while free oxygen may be present, I have provided a lubricating system now to be described.

In the tank 48 is a stratified body of an unctuous aqueous liquid such as a solution of soap and water or a suspension of graphite in water designated by numeral 49 underlying a layer of oil 50 with which it is immiscible. The outlet pipe 51 is connected to tank 48 at the lowest part of the tank and therefore when plunger pump 52, driven from the turbine by gearing not shown, begins to withdraw lubricant from the tank 48 the aqueous liquid is first supplied to the mechanism and is in such quantity as to provide lubrication during the interval that there is any likelihood of pure oxygen being present in the mechanism. However, as the run is continued the oil reaches pipe 51 and is the lubricating agent thereafter. It is to be noted that in torpedoes using compressed air instead of oxygen it is perfectly safe to lubricate with oil, but owing to the use of oxygen to prevent the formation of a wake, the precautions as to lubrication herein described must be taken

4
for an interval at the beginning of the torpedo run.

Fig. 6 shows a modification of the devices above described whereby a non-combustible gas, such as carbon dioxide in liquid form, indicated at 53, under high pressure in a tank 54 may be utilized to advantage. This gas may be permitted to expand to apply pressure through pipe 55 to the lubricant in tank 50 and may be carried by pipes 56 and 57 to operate the gyroscopic steering mechanism and the depth engine respectively. Tank 54 may also be connected by pipe 58 to the reducing valve 20 so that when starting lever 59, connected to the starting valve by a pipe 60, is tripped the gas under pressure from tank 54 will be applied to the turbine 26 to set the turbine in operation until the gases from the combustion chamber suffice for that purpose, the duration of passage of the gas to the turbine being automatically controllable by a valve 61.

The invention described herein may be manufactured and used by or for the Government of the United States of America for governmental purposes without the payment of any royalties thereon or therefor.

I claim:

1. In a thermal power system using substantially pure oxygen as a supporter of combustion, a flask to contain water and oxygen under pressure, a collapsible container for fluid fuel in said flask whereby said fuel is held under the same pressure as are said oxygen and water, a combustion device to burn said fuel in the presence of oxygen and water, means to supply oxygen, fuel and water to said device in suitable proportions, a prime mover connected to said device to receive products of combustion therefrom and to be driven by said products, and means connected to lubricate said prime mover with an unctuous aqueous liquid that is non-reactive with oxygen for an interval at the beginning of operation of said prime mover and thereafter to lubricate said prime mover with oil, said lubricating means including a container having in it a volume of said liquid and a supernatant volume of oil.

2. In a torpedo, a flask to contain a gaseous supporter of combustion and water under pressure, a collapsible container for fluid fuel in said flask, and means fixedly connecting a portion of said container to said flask and means slidably connecting another portion of said container to said flask to prevent said container from shifting its position in said flask.

3. In a torpedo, a flask to contain a gaseous supporter of combustion and water under pressure, a collapsible container for fluid fuel in said flask, means to prevent said container from shifting its position in said flask, and a perforated tube in said container extending longitudinally of said container adjacent the lower wall thereof.

4. In a torpedo, a flask to contain, under pressure, a supporter of combustion and water, a collapsible container for fuel in said flask, members fixed to the wall of said flask to lie adjacent said container longitudinally thereof, means connecting said container to said member to prevent longitudinal shifting of said container, arcuate members fixed to the wall of said flask and extending transversely of said container, and loop elements fixed to said container and slideable on said arcuate members.

5. In a torpedo, a flask to contain, under pressure, a supporter of combustion and water, a collapsible container for fuel in said flask, members fixed to the wall of said flask to lie adjacent said

container longitudinally thereof, means connecting said container to said member to prevent longitudinal shifting of said container, arcuate members fixed to the wall of said flask and extending transversely of said container, loop elements fixed to said container and slidably on said arcuate members, and a radially rigid perforated tube in said container lying longitudinally thereof of adjacent the lower wall thereof.

6. A method of lubricating the moving parts of mechanism that initially may be, for an interval, in the presence of substantially pure oxygen under pressure, comprising the steps of providing a stratified body of an unctuous aqueous liquid and oil, wherein the quantity of said liquid is proportioned to suffice for the lubrication of said parts during said interval, beginning the lubrication with said liquid and immediately continuing the lubrication with said oil after all the liquid has been used.

7. A method of lubricating the moving parts of mechanism that initially may be, for an interval, in the presence of substantially pure oxygen under pressure, comprising the steps of providing a stratified body of oil and a solution of soap and water, wherein the quantity of said solution is proportioned to suffice for the lubrication of said parts during said interval, beginning the lubrication with said solution and immediately continuing the lubrication with said oil after all of said solution has been used.

8. A method of lubricating the moving parts of mechanism that initially may be, for an in-

terval, in the presence of substantially pure oxygen under pressure, comprising the steps of providing a stratified body of oil and of graphite suspended in water, wherein the quantity of said graphite and water is proportioned to suffice for the lubrication of said parts during said interval, beginning the lubrication with said suspension of graphite in water and immediately continuing the lubrication with said oil after all of said graphite and water has been used.
